ATVS.

UNITED STATES PATENT OFFICE.

WILLIAM A. PARMENTER, OF BROCKTON, MASSACHUSETTS, ASSIGNOR TO C. S. PIERCE COMPANY, OF BROCKTON, MASSACHUSETTS, A CORPORATION OF MASSACHUSETTS.

MACHINE FOR MAKING PICKERS.

1,392,259.

Specification of Letters Patent. Patented Sept. 27, 1921.

Application filed November 4, 1920. Serial No. 421,798.

To all whom it may concern:

Be it known that I, WILLIAM A. PARMENTER, citizen of the United States, residing at Brockton, county of Plymouth, 5 State of Massachusetts, have invented a certain new and useful Improvement in Machines for Making Pickers, of which the following is a specification, reference being had therein to the accompanying drawings.

10 My invention has for its object a machine for the manufacture of pickers such as are used on the upper end of the picker staff of looms, these pickers being composed of leather or cowhide and having heretofore 15 been manufactured entirely by hand. The manufacture of pickers as heretofore practised has required the expenditure of a great deal of muscular strength, particularly in wrapping or folding a strip of leather into 20 shape. My present invention has for its object to provide a machine or device by which this operation may be performed without any considerable exertion on the part of the operator. The device embodying 25 my invention is very simple and enables the operator to produce pickers which are more uniform in character and at a much more rapid rate than has heretofore been possible.

30 The invention will be fully understood from the following description when taken in connection with the accompanying drawings, and the novel features thereof will be pointed out and clearly defined in the claims 35 at the close of this specification.

In the drawings, Figure 1 is a side elevation of a picker of the kind to be manufactured by the employment of the machine embodying my invention, the picker being applied to the upper end of the picker staff.

40 Fig. 2 is a top plan view of the picker shown in Fig. 1.

Fig. 3 is a side elevation of the machine embodying my invention.

45 Fig. 4 is a top plan view of the machine.

Fig. 5 is a side elevation of the front part of the machine showing the position of the parts at one stage during the manufacture of the picker.

50 Fig. 6 shows the position of the parts shown in Fig. 5 as the picker is about to be withdrawn from the mandrel.

Referring now to the drawings, at 11 is shown a bracket by means of which the machine is bolted to a bench. This bracket

comprises a member *a* which is secured to the bench and a member *b* at right angles thereto. Said members lie in vertical planes. Secured to the member *b* are two guide rods 12 and 13 which project forwardly toward the operator who stands in front of the machine. On the front of the guide rods 12 and 13 is secured a crossbar 14. The bracket 11, guide rods 12 and 13 and crossbar 14 from a heavy rigid structure capable of supporting the strain to which the machine is subjected. On a side of the crossbar 14 is located a boss *c* within which is an axle 15 provided with a crank 16 and a handle 17 by which the axle may be rotated. Secured to the end of the axle 15 which is opposite the handle 17 is a mandrel 18 which is of the shape of the hole *d* to be formed in the picker blank. This mandrel is rectangular in section and tapers slightly, the smaller end being that toward the left of the operator, as seen in Fig. 4. The mandrel 18 has a slot 19 milled lengthwise and on an angle to receive the end of the strip of leather which is to be made into a picker. 80 The mandrel has a sharp edge as indicated at the point *e* in Fig. 3, and the strip of leather in the manufacture of the picker is bent sharply over this edge and thereby prevented from pulling out of the slot by the strain to which it is subjected. The crossbar 14 has formed in its vertical slot 20 which is slightly larger than the cross-section of the mandrel. This slot extends only part way through the crossbar 14, as will be seen 90 by the dotted lines in Fig. 4. This slot is of a size to receive the mandrel and to permit the mandrel to be drawn to the right, as viewed in Fig. 4, for the purpose of withdrawing the picker blank from the mandrel 95 after the operation of winding the picker blank has been completed.

On the guide bars 12 and 13 is located a crosshead 21 which carries a stud 2 on which is revolvably mounted a roller 3. This roller is of the diameter such that it extends beyond the front edge of the crosshead 21. Between the crosshead 21 and the member *b* of the bracket 11, is located a heavy spring 24 which pushes the roller 3 forcibly toward the mandrel. In practice, I find it convenient to place the spring around a guide rod 25 secured at its front end to the crosshead 21 and freely slidable in a thimble 6 which is screw-threaded into the member *b* 110

of the bracket 11. By changing the position of this thimble 6 in the bracket, the tension of the spring may be adjusted as desired, and the thimble and slide rod 5 25 serve to prevent displacement of the spring 24.

At 27 is shown a stop secured to a leaf spring 28 by a screw 29. The leaf spring 28 is secured to the crosshead 21 by a screw 10 30. This stop 27 is so located that it is normally in the space between the crossbar 14 and the crosshead 21 and serves to hold the picker blank away from the roller when 15 the picker blank is about to be removed from the mandrel.

The operation of my machine is as follows:—The strip of leather *f* shown in dotted lines in Fig. 1 from which a picker blank is to be made, has a skived or beveled 20 surface, as shown at *g* and is properly tempered, so that it is in a relatively soft, pliable condition. The square end of the blank is inserted in the slot 19, the mandrel being at this time in the position shown in 25 Figs. 3 and 4. The operator then turns the crank in the direction indicated by the arrow in Fig. 3, and at the same time holds the leather sufficiently to steady it and prevent its displacement from the slot.

30 The rotation of the mandrel 18 brings the leather in contact with the roller 3, and the spring 24 forces the roller against the leather. The leather is, therefore, bent and wound about the mandrel into the shape

35 shown in Figs. 5 and 6. When the machine reaches the position shown in Fig. 5, the crossbar 14 and the guide 21 which carries the roller 3 are most widely separated and the leather on the mandrel 18 is subjected 40 to the maximum pressure from the spring 24. The operator stops the movement of the machine at this position and turns down the skived or beveled end *g* of the leather into contact with the previous layer of

45 leather and drives in a tack 7, as shown in Figs. 5 and 6. This tack is sufficient to hold the picker blank in this condition until the parts have been finally secured in place by rivets 32 during subsequent operations.

50 The operator then turns the handle 17 backward through ninety degrees, and the stop 27 which has dropped into the position shown in Fig. 6, prevents the roller 3 from following the leather, thus making it easier 55 for the operator to remove the blank from the mandrel.

To remove the blank from the mandrel, the operator pulls the handle 17, the axle 15 and the mandrel 18 mounted thereon to the 60 right, as viewed in Fig. 4, the end of the mandrel entering the slot 20 in the crossbar 14 as the picker blank slips off the end of the mandrel.

The picker blank is then ready to be subjected 65 to subsequent operations, including

the insertion member 33, the riveting, and the pressing and molding into final shape, these operations having no bearing on the use of the machine embodying my invention.

What I claim is:—

1. A machine of the character described comprising a mandrel on which the strip is to be wound, a crossbar, a plurality of guide members projecting from said crossbar, a crosshead slidably mounted on said guide members so as to slide toward and from said crossbar, a pressure roller rotatably mounted on a shaft projecting laterally from said 70 slideable crosshead, and a spring which exerts pressure on said crosshead to hold said roller in yielding engagement with the strip being wound on the mandrel.

2. A machine of the character described comprising a mandrel on which the strip is to be wound, a crossbar, a plurality of guide members projecting from said crossbar, a crosshead slidably mounted on said guide members so as to slide toward and from said crossbar, a pressure roller rotatably mounted on a shaft projecting laterally from said 80 slideable crosshead, a spring which exerts pressure on said crosshead to hold said roller in yielding engagement with the strip being wound on the mandrel, a bracket with which said guide members are rigidly connected, and a rod rigidly connected at one end with said slideable crosshead, the other end being 85 slideable in a slot in said bracket.

3. A machine of the character described comprising a mandrel on which the strip is 100 to be wound, a crossbar, a plurality of guide members projecting from said crossbar, a crosshead slidably mounted on said guide members so as to slide toward and from said crossbar, a pressure roller rotatably mounted on a shaft projecting laterally from said 105 slideable crosshead, a spring which exerts pressure on said crosshead to hold said roller in yielding engagement with the strip being wound on the mandrel, a bracket with which said guide members are rigidly connected, and a rod rigidly connected at one end with said slideable crosshead, the other end being 110 slideable in a slot in said bracket, said pressure spring being mounted on said 115 last mentioned rod.

4. A machine of the character described comprising a crossbar, a shaft passing through the crossbar and rotatable therein, a rotary mandrel of elongated form in cross 120 section mounted on said shaft and slideable axially toward the crossbar, a roller mounted on a member which is movable toward and from the periphery of the mandrel, and a spring to force the roller toward the mandrel, the crossbar being formed with an elongated slot into which the mandrel is 125 receivable when the mandrel is in position for its elongated diameter to be presented to the elongated diameter of the slot. 130

5. A machine of the character described comprising a mandrel, an axle for the mandrel, a crossbar supporting the axle, said crossbar being slotted to permit endwise 5 movement of the mandrel when in one position, means for rotating the mandrel, and a pressure member adapted to exert pressure on the strip as the mandrel is rotated on said axle.
- 10 6. A machine of the character described, comprising fixed guide members, a crossbar thereon, a rotatable mandrel mounted on the crossbar, a crosshead slidable on the guide members, a spring to force the crosshead toward 15 the crossbar, a roller on the guide, and a stop insertible between the crossbar and the crosshead.
- 20 7. A machine of the character described comprising fixed guide members, a crossbar at the end thereof, a mandrel, an axle for the mandrel passing through the crossbar and rotatable therein, said crossbar being slotted to permit the mandrel to slide lengthwise of the axle when in one position, 25 a crosshead slidable on the guide members, a spring to force the crosshead toward the crossbar, a roller on the crossbar, and means for rotating the mandrel.
8. A machine of the character described comprising a bracket, a plurality of parallel 30 guide rods projecting therefrom, a crossbar fixedly mounted on said rods, a crosshead slidably mounted on said rods intermediate said bracket and said crossbar, a mandrel mounted on an axle which passes through 35 said crossbar, a roller mounted on a shaft projecting from said crosshead, and a spring which presses the crosshead toward the crossbar so as to press the roller against the windings on the mandrel. 40
9. A machine of the character described comprising a bracket, a plurality of parallel guide rods projecting therefrom, a crossbar fixedly mounted on said rods, a crosshead slidably mounted on said rods intermediate 45 said bracket and said crossbar, a mandrel mounted on an axle which passes through said crossbar, a roller mounted on a shaft projecting from said crosshead, a spring which presses the crosshead toward the crossbar so as to press the roller against the windings on the mandrel, and a rod on 50 which said spring is mounted, said rod having one end fast to said crossbar and the other end slidable in a slot in said crosshead. 55

In testimony whereof I affix my signature.

WILLIAM A. PARMENTER.
